DRAFT GEAR FOR RAILWAY CARS

Willie T. Stephens, Abbeville, S. C.

Application August 14, 1939, Serial No. 290,065

1 Claim. (Cl. 213—46)

The present invention relates to improvements in draft gear for railway cars, and has for an object to provide a spring draft gear which will absorb the shocks and jars and the vibration incident to the starting and stopping of passenger and freight trains, including the long modern freight trains of heavy and heavily-laden cars.

Another object of the invention is to provide a spring-suspended draft gear for vehicles of any kind in which a cushion will be interposed between the vehicles coupled together so that the pulling or pushing strains may be absorbed in the convolutions of the springs and minimized or eliminated in their transfer to the sills and bodies of the cars.

10 bodies of the cars.

A further object of the present invention is to provide a draft gear structure for freight and other cars which will not only minimize the shocks to the cars but also save the draft gear

20 and consequently reduce damage through breakage of draw heads, draw bars and other parts which are subjected to severe shocks particularly when freight cars are coupled by the method of putting the freight car in motion and then releasing it to run against a string of cars to which it is to be coupled to form a train.

25

The invention also contemplates an installation on railway freight and other cars which will reduce damage and rough-handling claims 30 as to the merchandise shipped in the freight cars.

With the foregoing and other objects in view, the invention will be more fully described hereinafter, and will be more particularly pointed out in the claim appended hereto.

In the drawings, wherein like symbols refer to like or corresponding parts throughout the several views,

Figure 1 is a top plan view with parts broken away and parts shown in section of the chassis of a railway car showing a device according to the invention applied thereto.

Figure 2 is a longitudinal vertical section taken on the line 2-2 in Figure 1.

45 Figure 3 is a similar section taken on the line 3-3 in Figure 1.

Figure 4 is a transverse vertical section taken on the line 4-4 in Figure 1.

Figure 6 is also a transverse vertical section

taken on the line 6—6 in Figure 1.
Referring more particularly to the drawings
7 designates the side sills and 8 and 9 the end
55 sills which compose generally the conventional

frame of a railway passenger or freight car; and 10 and 11 represent the vertical webs of the center sills, which as more particularly shown in Figure 5 are spaced apart at the center portion of the car and have their flanges 12 and 13 disposed mutually outward.

At one end of the car is a draw head 14 carried upon the draw bar 15. This draw bar 15 has a slideable and loose fit through an opening 16 in the transverse sill 8. 10

Such draw bar 15 is of substantial length and it slidingly fits in the space between the webs 10 and 11 of the center sills, being guided generally but with some looseness by a transverse draft key 17 which fits through an opening 18 in the draw bar 15, such opening being slightly wider than the diameter of key 17 to allow for a certain loose play.

The key 17 slides in slots 19 and 20 in the webs 10 and 11 of the center sills. As shown in Figure 2, the shank 17 of the draft key is preferably rectangular in cross section with its longer sides parallel and horizontal and sliding rather snugly in the upper and lower walls of the slots 19 and 20. The opening 18 is slightly wider in the horizontal dimension than the horizontal width of the key 17 which produces the loose play heretofore referred to in the horizontal sense and direction.

At one end the draft key 17 may be formed with a head 21 larger than the slot 20 so as to confine the key against casual or accidental movement through the slot 20. 30

At its other end the key 17 may be fitted with a block 22 which serves the same purpose with reference to the slot 19. A cotter pin 23 or other form of fastening device may pass through both the key 17 and the block 22 for the purpose of removably holding the latter upon the key. 35

The shank 17 of the draft key forms, besides a guide for the draw bar 15 at an intermediate portion thereof remote from its bearing in the opening 16, an abutment for the two proximate ends of coil springs 24 and 25. The end convolutions of these springs abut against the flat vertical faces of the key 17 and the helices of the coil springs 24 and 25 are coiled about the draw bar 15. The outer spring 25 has its outer helix abutting against the inside of the sill 8 or against a plate 26 provided at this point. 40 45 50

The inner end of the companion coil spring 24 abuts against a block 27 affixed in any suitable manner to the center sills 10 and 11 and having an opening through which the inner end portion of the draw bar 15 slides and has a bearing. A 55

cotter key 28 in the end of the draw bar 15 may prevent the withdrawal outwardly of such draw bar. Therefore it will be seen that the inner end of this draw bar is floating and that it may 5 have a certain range of sidewise movement due to the enlargements of openings 16 and 18 here- tofore referred to.

At the other end of the car is a draw head 29 on the end of a sliding draw bar 30 which is 10 fitted rather tightly through an opening 31 in the cross sill 9. This draw bar 30 is not as long as the companion draw bar 15, and unlike the latter, the draw bar 30 is formed with a vertically thickened and reinforced portion 32 in order to 15 better withstand the formation of the slot 33 which is elongated in a horizontal direction as compared with the horizontal width of the trans- verse draft key 34. The shank of this draft key is also formed substantially rectangular as in- 20 dicated in Figures 2 and 3. There is a substan- tial amount of loose play between the horizontal dimension of draft key 34 and the end walls of the slot 33. An enlarged head 35 is formed on the thickened part 32 of the draw bar 30, which 25 enlarged head 35 is at the inner end of slot 33 and adapted to receive the impact of the shank of the transverse draft key 34.

The draft key 34 extends slidably in slots 36 and 37 made in the webs of the center sills, such slots being located horizontally to both sides of the key 34 so that like the slots 19 and 20 they permit the key to have a wide range of horizontal sliding movement.

Exteriorly of the center sills, the draft key 34 passes through cross-heads 38 and 39. Cross- head 38 is formed with a countersunk socket 40 to receive the head 41 of the draft key 34; such construction being best seen in Figure 4. The other end of the draft key 34 is received through a rectangular opening in the cross-head 39 and removably secured therein by a cotter pin or other fastening 42.

One of the cross-heads 38 carries trunnions 43 and 44 to freely penetrate for a distance into the end convolutions of coil springs 45 and 46.

At its outer end the coil spring 45, or rather the end convolutions thereof are received over a trunnion 47 which may be carried by the sill 9 or other appropriate part of the frame work of the car. The proximate ends of the trunnions 43 and 47 will always be remote to permit the coil spring 45 to compress.

The inner end of the inner coil spring 46 as to its end convolutions is received over and guided by a trunnion 48 which is carried by a casting or other appropriate part 49 affixed by bolts 50 or other appropriate fastenings to the web of the center sill on its outer side.

On the opposite side of the device, the cross- head 39 carries trunnions 51 and 52 for receiving the near end convolutions of coil springs 53 and 54.

Other trunnions 55 and 56 receive the opposite or remote end convolutions of these springs and are respectively carried by the transverse sill 9 and a block or casting 57 affixed as by bolts 58 or other appropriate fastenings to the outside surface of the opposite center sill.

Whereas at one end of the car the draw bar 70 15 and its coil springs are disposed centrally in the line of draft and confined in the space be- tween the webs of the two center sills of the car frame, at the opposite end of the car the draw bar 30 alone slides within this center space and along this center line, but the springs for cush-

ioning its movement are disposed outside the center line of draft and outside the space between the center sills.

In fact the outside walls of the vertical webs 10 and 11 of the center sills are utilized in part 5 to guide the axial movement of the coil springs, the tendency of which, on compression, is to diverge from the true axial line or to buckle or bulge outwardly, which is detrimental to the spring action which it is their function to per- 10 form.

The coil springs 24 and 25 at the right hand end of the car will be guided throughout their 15 entire length by means of the draw bar 15 which passes entirely throughout the helices thereof. But in the case of the springs at the other end of the car, these springs are only guided as to their end convolutions by the trunnions extending for a short ways thereinto, leaving the balance or intermediate portions of the springs un- 20 confined except by the webs of the center sills. The webs 12 and 13 of the sills will prevent the center portions of these springs from buckling up or down unduly and I have provided guards for preventing the outward bulging of the springs 25 such guards consisting of plates 59 affixed to the sills or to other appropriate parts and having up- wardly extending and curved spaced fingers 60 having slots 61 therebetween.

These fingers will be slightly spaced from the 30 coil springs so as not to interfere with the coil springs growing in diameter to some extent but the fingers are wide enough to span at least two convolutions of the spring to prevent the spaces between the convolutions bridging over the fin- 35 gers 60.

The slots 61 preferably open upwardly through the upper edge of the guards. These open ends and the slots 61 permit of inspection of the 40 springs, and also prevent foreign matter from wedging between the guards and the springs to the possible detriment of the movement of the convolutions, and such slots and openings permit of the insertion of instruments between the 45 fingers 60 to clean out the springs or to free the convolutions thereof from the guards.

In the use of the device, both draw bars will be cushioned in the movement in the line of the draft both inwardly and outwardly. The coil 50 spring 25 will be compressed between the draft key 17 and the cross sill 8 when the draw bar 15 is pulled outwardly as in the act of starting the car from a standing position; or when accelerat- 55 ing the speed of the train when moving in the right hand direction as viewed in Figures 1 and 2.

The coil spring 25 is in reality not connected anywhere to the draw bar 15 but reacts against cross sill 8 and draft key 17. Coil spring 24 en- gages against the opposite side of key 17 and 60 pushes against block 27.

When cars collide and draw bar 15 is pushed inwardly, that is shifted to the left in Figure 1, the key 17 compresses coil spring 24 against fixed abutment 27 and cushions this inner movement. The draw bar and its key 17 virtually float be- 70 tween the springs 24 and 25. Any binding ten- dency is overcome by the loose play of the draw bar 15 in the opening 16 and the loose play af- fered by the slots 18, 19 and 20.

This right hand construction may be used for passenger car rigging or light vehicles, and it may be used at one or both ends of the car. Preferably it will be used in conjunction with the side spring arrangement shown at the left

end of Figure 1. The term side spring arrangement is used in contradistinction to the center spring arrangement where the coil springs 24 and 25 are centrally of the line of draft as shown at the right hand side of Figure 1. A certain cooperation exists between the two forms of devices when mounted upon the same car or vehicle.

In the operation of the side form of spring as shown at the left hand side of Figure 1, when strain is put upon the draw bar 30 to draw the same out, that is in a left hand direction, the draft key 34 and the connected cross heads 38 and 39 will be drawn upon compressing the coil springs 45 and 53 and thus cushioning this action and absorbing the shocks and jars incident thereto and minimizing these shocks and jars as far as the body of the car or vehicle is concerned, and in many cases eliminating such shocks and jars from being transmitted to the car or vehicle. When the draw bar 30 is moved in the other direction, that is in the right hand direction as viewed in Figure 1, as when cars are driven against one another for the purpose of coupling the same into a train, the draft key 34 with its cross-heads 38 and 39 will be moving to the right thus compressing the springs 46 and 54, these springs thus absorbing the shocks and jars and minimizing and eliminating at times the impression of those shocks transmitted to the car or vehicle.

The spring devices at opposite end of the car will cooperate in that when a pull is exerted to the right on draw bar 15 it will not only compress its spring 25, as heretofore described, but it will also compress the springs 45 and 53 of the left hand side spring device because of the attachment of the draw head 29 to the draw head of the next car to the left, the inertia of said next car creating a movement of draft key 34 to the left and compressing springs 45 and 53. In like manner shocks and jars coming from a right hand direction against the right hand end of draw bar 15 and transmitted to the car will tend to compress springs 46 and 54 at the other end of the car due to the fact that the car tends to move to the left along draw bar 30, the draw bar being held stationary by the inertia of the next car to the left which is coupled to draw head 28. The right hand device comprises the springs 24 and 25 at one end of the car, being centrally disposed, and between the pairs of side springs of the device at the left end of the car, tends to stabilize the device at the left and the device at the left tends to stabilize the right hand central device, the line of thrust being in three planes, the one plane being a central plane at one end of the car and at the other end of the car there being two parallel planes offset to opposite sides of the said central plane.

The loose slot 16 at the one end and the tight slot 31 at the other end will tend to permit of the adjustment and accommodation of the draw head 14 while the draw head 28 will be held to a central alignment so that a certain lateral flexibility will be permitted by the contribution of the two devices at opposite ends of the car.

The fact that the opening 31 is tight will not

have any binding effect upon the coil springs or the cross-heads because of the loose play of slot 33 and of the slots 36 and 37 and of the loose plate of the trunnions of the cross-heads in the near ends of the coil springs.

With the use of the springs the train may be started with less effort and with no hard knocks on loading or passengers. When switching cars in yards or making cars into trains, the cars equipped with the improved device will easily stand a shock of say twelve to fifteen miles per hour without breakage to draw heads or other parts.

The springs also eliminate shocks due to shifting of light merchandise and rough freight and will eliminate many damage claims and claims for rough handling of merchandise.

The draft keys have play to move with the springs in order to give springs full advantage.

It is obvious that various changes and modifications may be made in the details of construction and design of the above specifically described embodiment of this invention without departing from the spirit thereof, such changes and modifications being restricted only by the scope of the following claim.

What is claimed is:

Draft gear for railway cars and the like comprising a car frame having an end sill and spaced center sills with slots therein, a transverse key 30 slidably and non-rotatably mounted in said slots, a draw bar extending between said center sills connected with said key and slidably through an opening in said end-sill, cross-heads on the end portions of said key, coil springs on each side of said crossheads and lying outwardly of said sills, means carried by said cross-heads and sills for supporting and positioning said coil springs, each of said center sills including a vertical wall and top and bottom outwardly extending horizontal parallel webs, said vertical wall and webs providing generally a housing for one of said coil springs, said spring extending longitudinally of and close to said vertical wall, whereby the vertical wall acts as a guide for the spring during its axial movement, said top web overlying and being close to said spring, thereby preventing undue upward buckling of the spring, said bottom web underlying and being close to said spring, thereby preventing undue downward buckling of the spring, and a guard for each spring fixed to the lower part of each sill and extending outwardly and thence upwardly in spaced substantially parallel relation to the vertical wall of the center sill, the upper free portion of each guard being slotted at regular intervals to provide spaced fingers, said fingers being slightly spaced from its spring, thereby permitting the spring to enlarge its diameter to some extent and at the same time preventing undue outward bulging of the spring, said fingers terminating at points below the top of the spring and being sufficiently wide to span at least two convolutions of the spring.

WILLIE T. STEPHENS.
